VANITY CASE

Gloria Gigliuto, 19 Kingston St.,
Wethersfield, Conn. 06279

Filed Aug. 28, 1967, Ser. No. 8,399

Term of patent 14 years

(Cl. D87—1)

FIG. 1

FIG. 2

FIG. 3

FIG. 4

FIG. 5

FIGURE 1 is a perspective view of a vanity case embodying my new design with the cover closed;

I claim:

The ornamental design for a vanity case, as shown.
